FRED A. GERLING, OF BOISE, IDAHO

FLUID PRESSURE ENGINE

Application filed January 18, 1930. Serial No. 421,778.

My invention relates to improvements in fluid pressure engines, operated upon steam or compressed air or other gases under pressure.

In accordance with my invention, I provide an engine to be driven by steam, compressed air or other fluid pressure. The engine embodies a unit of two cylinders, with pistons operating therein. The arrangement renders it possible to eliminate the use of stuffing boxes and glands, and affording free access to the pistons and their packing rings and the connections between the pistons and the connecting rods. By employing the two cylinders and pistons therein, the entire effective areas of the pistons are utilized, thus obtaining the maximum power and efficiency. The opposite ends of the cylinders are closed, and each cylinder has inlet and exhaust valves. The means to shift the valves serves to close both valves of each cylinder, as the piston approaches the end of its stroke, prior to opening the inlet valve, for providing compression in the cylinder, as the out stroke commences. The engine also embodies a centralizing mechanism serving to connect the reciprocating pistons with a rotary driven member, and the arrangement is such that equal pressure is applied to the opposite sides of the pistons and there is no tendency for the pistons to tilt and become worn upon their lower side. The arrangement also eliminates the use of cross-heads and gibs. The engine also embodies an auxiliary rotatable timing element connected with the pistons of the engine to limit their reciprocatory movements, and the timing element may be rotated in either direction independently of the direction of rotation of the driven power distributing element. The connections between the centralizing mechanism and the rotatable driven member is such that there are no dead centers for the connections.

In the accompanying drawings, forming a part of this specification, and in which like numerals are employed to designate like parts throughout the same,

Figure 1 is a side elevation of the complete engine, embodying my invention,

Figure 2 is a diagrammatic view of the valve actuating mechanism,

Figure 3 is a plan view of the complete engine,

Figure 4 is a vertical section taken on line 4—4 of Figure 3,

Figure 5 is a transverse section taken on line 5—5 of Figure 4,

Figure 6 is an enlarged side elevation of the engine, the end portions being broken away,

Figure 7 is a plan view of the engine shown in Figure 6.

Figure 8 is an enlarged vertical section taken through line 8—8 of Figure 1, and,

Figure 9 is an enlarged vertical section taken through line 9—9 of Figure 1.

In the drawings, wherein for the purpose of illustration is shown a preferred embodiment of my invention, the numeral 15 designates a base. Mounted upon the left end of this base are uprights or standards 16, having bearings 17 rotatably receiving a transverse shaft 18. A fly wheel 19 is rigidly mounted upon the shaft 18, to turn therewith, and this shaft also rotates a pulley 20. A timing element or crank-disc 21 is carried by the shaft 18 and rotates therewith.

Uprights or standards 22 are rigidly mounted upon the base 15, near its right end and have bearings 23, rotatably receiving a transverse shaft 24. This transverse shaft has a power distributing pulley 25 rigidly mounted thereon.

The shaft 24 carries a power transmitting unit embodying a pair of spaced fly wheels 26, which are rigidly secured to the shaft 24, for rotation therewith. Rigidly secured to the inner sides of the fly wheels 26, Figure 5, are annular bands or flanges 27, to be engaged by intermittently operating gripping devices. These gripping devices embody separate arms or levers 28 and 29, preferably diametrically oppositely arranged and provided at their inner ends with separate hubs 30 and 31 which are independently pivotally mounted upon the shaft 24. Particular attention is called to the fact that these operating arms 28 and 29 are independently pivoted upon the common shaft 24. The op-

erating arm 28 has its upper end provided with a fork 30 receiving a generally radial body portion 31 of a gripping device. This body portion is pivoted near its outer end to the fork 30, as shown at 32. The body portion 31 is provided with outer and inner arms 33 and 34, preferably formed integral therewith, and these arms carry cross-heads 35 and 36, provided with gripping jaws 37 and 38, respectively, arranged to grip above and beneath the flanges or bands 27, as shown. The movement of the radial body portion 31 upon its pivot in a direction to release the jaws from gripping action with the bands 27 is limited by an adjustable bolt 39, having screw-threaded engagement with a bracket 40 carried by the fork 30. The operating arm 29 is provided at its outer end with a gripping device 41, identical with the gripping device carried by the arm 28, except that the gripping jaws 37 and 38 face in an opposite direction. The gripping device carried by the arm 28, Figure 4, is adapted to turn the fly wheel 26 when the arm 28 is swung to the right, while the gripping device 41 carried by the arm 29 is adapted to turn the fly wheels in the same direction when swung to the left. These gripping devices, therefore, operate in opposite directions to effect a turning movement of the fly wheel. It is thought to be unnecessary to describe the gripping device 41 further in detail.

Arranged upon the inner portion of the base 15 are vertical supports or uprights 42 and 43, having cylinders 44 and 45, rigidly mounted thereon. Mounted to reciprocate within these cylinders are pistons 46 and 47, respectively, rigidly connected with piston rods 48 and 49, preferably by means of screw-threads, and the inner ends of these piston rods have screw-threaded engagement with a cross-hub 50 and are locked thereto by clamping nuts 51, or the like. This cross-hub has lateral extensions 52, upon which are pivotally mounted centralizing connecting links 53, by means of pins or pivots 54, the pivots passing through the center of the connecting links. Connecting rods 55 are pivoted upon the pins 54 outwardly of the links 53 and extend to the left for pivotal connection with the timing element or crank-disc 21, as shown at 56. The connecting rods 55 are offset inwardly at 57, as shown. By the use of two cylinders and pistons therein, glands or stuffing boxes are eliminated and the inner ends of the cylinders are left open, to afford free access to the pistons and their rings. Further, the entire areas of the pistons are acted upon by the steam or the like, thus increasing the power and efficiency of the engine.

The numerals 58 and 58' designate centralizing levers pivoted at their upper ends, as shown at 59, with a support 60. The numerals 61 and 61' designate a pair of co-

acting centralizing levers which are pivoted at their lower ends, as shown at 62, with a support 63. These centralizing levers are pivotally connected with the links 53, as shown at 64 and 65. A connecting rod 66 extends between the upper ends of the centralizing levers 61 and 61' and is pivotally connected therewith, as shown at 67. This connecting rod extends to the right and projects into the fork 30 and is pivotally connected with the inner end of the body portion 31 of the gripping device, as shown at 68, Figures 4 and 5. A lower connecting rod 69 extends between the lower ends of the centralizing levers 58 and 58' and is pivotally connected therewith, as shown at 70. The rod 69 extends to the right and enters the forked end of the arm 29 and is pivotally connected with the body portion 31 of the gripping device 41, as shown at 71, Figure 5. It is thus seen that the pairs of centralizing levers 58 and 58' and 61 and 61' swing in unison, and their swinging movement is imparted to the fly wheels 26 through the gripping devices, which impart an intermittent force to the same, to cause their rotation, one gripping device being active while the other is inactive. The gripping devices preferably swing through an arc of about 75° and can not become arranged at dead center, with respect to the fly wheels 27.

The cylinder 44, see more particularly Figure 2 has an inlet port 72, in communication with a fluid pressure supply pipe 73. This inlet port is covered and uncovered by means of an oscillatory valve 74, turned by a crank 75. The cylinder 44 also has an exhaust port 76 covered and uncovered by an oscillatory valve 77, turned by a crank 78. The cylinder 45 has an inlet port 79, covered and uncovered by an oscillatory valve 80, turned by a crank 81. The port 79 is in communication with a fluid pressure supply pipe 82, and pipes 73 and 82 have communication with a common fluid pressure supply pipe 84. The cylinder 45 has an exhaust port 85 covered and uncovered by an oscillatory valve 86 turned by means of a crank 87.

Valve shifting mechanism is provided to alternately open and close the inlet valve 74 and exhaust valve 86, comprising vertically swinging levers 88 and 89, pivotally supported at their lower ends, shown at 90. These levers are arranged upon the same side of the engine with the centralizing arm 58. The lever 88 is provided at its upper end with a fork 91, having its ends attached to suitably stiff retractile coil springs 92, see more particularly Figure 6, which extend inwardly for connection with the eyes of a coupling 93, which is rotatably mounted upon a pin or bolt 94, also rotatably mounted in an opening formed on the outer end of the crank 75. The lever 89 has a fork 95, which is connected by identical means including springs 92 and as-

sociated elements with the crank 87. The levers 88 and 89 are connected by means of a rod 96. The exhaust valve 77 is opened and closed by means of a lever 97, connected with the crank 78 by the identical yielding connecting means described in connection with the lever 88, including the springs 92.

The inlet valve 80 is opened and closed by means of a lever 98, connected with the crank 81, by yielding means identical with that described in connection with the lever 88 including the springs 92. The levers 97 and 98 are disposed upon the opposite side of the cylinders 44 and 45 with respect to the levers 88 and 89, and are pivotally supported at their lower ends, as shown at 99 to swing in a vertical plane longitudinally of the cylinders. The levers 97 and 98 are connected by a rod 100. As more clearly shown in Figure 7, the pins 94 carried by the cranks 75 and 78 are provided at their upper ends with heads or blocks 101, having openings for receiving adjustable eye-bolts 102, connected with a retractile coil spring 103. A stop 104 is arranged to limit the swinging movement of the crank 75 when the intake valve 74 is in the open position, while a stop 105 limits the movement of the crank when the valve 74 is in the closed position. A stop 106 limits the movement of the crank 78 when the exhaust valve 77 is in the closed position, and a stop 107 limits the movement of the crank 108 when the valve 77 is in the open position. When the cranks 75 and 78 are shifted into engagement with the corresponding stops, it is obvious that the spring 103 will retain them in such positions. The pins 94 carried by the cranks 81 and 87 are provided at their tops with heads or blocks 108, carrying adjustable eye-bolts 109, connected by a retractile coil spring 110. A stop 111 limits the movement of the crank 87 when the exhaust valve 86 is in the open position and a stop 112 limits the movement of the crank 87, when the exhaust valve is in the closed position. A stop 113 limits the movement of the crank 81 when the inlet valve 80 is in the closed position, and a stop 114 limits the movement of the crank 81 when the valve 80 is in the open position. The spring 110 serves to hold the cranks 81 and 87 in position when shifted to engage with the corresponding stops. Particular attention is called to the fact that when the cranks 75 and 78 are shifted past transverse dead center in either direction, the spring 103 will quickly snap the cranks to the ends of their movements, in engagement with the stops. The same action occurs with the cranks 81 and 87.

In view of the foregoing description, it will be seen that when the inlet valve 74 of the cylinder 44 is opened, exhaust valve 77 of this cylinder is closed, while the exhaust valve 86 of the cylinder 45 is opened and the inlet valve 80 is closed, and vice versa.

The numeral 115 designates a shoe carried by the upper end of a vertically swinging lever 116, which is pivoted between its ends upon the rod 96, as shown at 117. The lower end of this lever is connected with a retractile coil spring 118, the other end of which is attached to an arm 119 angularly adjustably secured to the rod 96. A link 120 is pivotally connected with the upper end of the lever 116 as shown at 121, and the link is provided at its outer end with a slot 122, receiving a bolt 123 secured to an arm 124, which is angularly adjustably attached to the rod 96. It is thus seen that the spring 118 and associated elements yieldingly oppose the outward swinging movement of the upper end of the lever 116, within limits, but when the end wall of the slot 122 engages the bolt 123, this outward swinging movement of the lever 116 is positively stopped. A shoe 125 is carried by the upper end of the lever 126, which is pivoted to swing in a vertical plane, between its ends, as shown at 127, upon the rod 96. A retractile coil spring 128 is secured to the lower end of the lever 126 and is attached to an arm 129 angularly adjustably secured to the rod 96. A link 130 is pivoted to the upper end of the lever 126 as shown at 131 and has a slot 132 at its outer end, receiving a bolt 133, carried by an arm 134 angularly adjustably secured to the bar 96. It is thus seen that the spring 128 and associated elements yieldingly oppose the outward swinging movement of the upper end of the arm 126, but when the end wall of the slot 132 engages the bolt 133, such outward swinging movement of the lever 126 is positively stopped. The shoes 115 and 125 are arranged upon opposite sides and in the path of travel of a roller or tripping element 135, which is mounted upon the centralizing lever 58, at a point near and above the connecting point 96.

When the centralizing lever 58 is in the vertical or neutral position, the roller 135 is equi-distantly spaced from the shoes 115 and 125 and it is obvious that this roller upon the swinging movement of the centralizing lever 58 will alternately engage these shoes, thereby shifting the rod 96 in opposite directions.

The shoe 136 is mounted upon the rod 110 by the identical means as described in connection with the shoe 115, and a shoe 137 is mounted upon the rod 100 by the identical means, as described in connection with the shoe 125. The shoes 136 and 137 are arranged upon opposite sides of a roller or trip element 138, carried by the centralizing lever 58'. The levers 58 and 58' swing in unison, as described.

By angularly adjusting arm 119 the tension of the spring 118 may be regulated. This spring may serve as a buffer for the shoe 115, and may also move the shoe before the bolt 123 engages the end wall of the slot 122, if

desired. The tension of the remaining corresponding springs may be regulated for the same purpose, if desired. The shoe 125 is set inwardly in advance of the shoe 137 and shoe 136 has the same arrangement with respect to the shoe 115.

Centrifugal means are employed to regulate the speed of the engine, comprising a centrifugal governor 139 of any well known or preferred type, which is so constructed that a vertical rod 140 will be lowered as the speed of the governor increases. The centrifugal governor is driven by means of a pulley 141, receiving its rotation from a belt 142 engaging the pulley 20. The vertically movable rod 141 is connected with a vertically movable valve element 143, included in a valve structure 144, connected in the pipe 73. The vertically movable rod 140 also has suitable connection with a vertically swinging bell crank lever 145, having connection with a rod 146, which is connected with a second bell crank lever 147, the horizontal arm 148 of which is connected with a vertically movable rod 149, connected with a vertically movable valve element 150 of a valve structure 151, connected in the pipe 82. It is thus seen that the centrifugal governor 139 will automatically regulate the volume of fluid pressure supplied to the cylinders, for regulating the speed of the engine.

The operation of the engine is as follows:

In the beginning of the cycle of operation, the pistons 46 and 47 are in the central position, and centralizing levers 58 and 58' are in the central vertical position, and rollers 135 and 138 out of contact with all shoes, as clearly illustrated in Figure 2. With the elements thus arranged, the inlet valve 74 of the cylinder 44 is open and exhaust valve 77 closed, while inlet valve 80 of cylinder 45 is closed and exhaust valve 86 is open. Steam or other fluid under pressure is now passing into the cylinder 44 moving the piston 46 to the right. This movement continues until the pistons 46 and 47 near their end stroke to the right. The centralizing levers 58 and 58' are swung to the right and rollers 135 are adapted to engage shoes 125 and 137, respectively, to shift the bars 96 and 100 to the right. The bars 96 and 100 swing the levers 88 and 89, and 89 and 98 to the right. The lever 89 first closes the exhaust valve 86, before the inlet valve 80 is opened, whereby both valves are closed before the piston 47 has reached the end of its right stroke, steam or the like being entrapped in the end of the cylinder 45 and compressed, the valve 86 remaining closed and valve 80 being shifted to the open position at about the time that the piston 47 reaches the end of its right stroke. Due to the action of the rod 96, the inlet valve 74 of cylinder 44 is closed shortly before the opening of the exhaust valve 77, thereby permitting of the completion of the right stroke of

the piston 46, due to the expansion of the steam or the like within the cylinder. When the piston 46 reaches the end of its right stroke, the exhaust valve 77 is opened and inlet valve closed, and steam will exhaust from the cylinder 44 when the pistons 46 and 47 travel to the left. When the piston 46 travels to the left and as it approaches the end of its left stroke, roller 138 first engages shoe 136 before roller 135 engages shoe 115, the action being to close the exhaust valve 77 prior to the opening of the inlet valve 74, whereby steam or the like is entrapped in the end of the cylinder 44 and compressed by the piston 46. At about the time that the piston 46 reaches the end of its left stroke, the exhaust valve 47 remains closed while inlet valve 74 is opened and steam is supplied into the cylinder 44, the pistons 46 and 47 then traveling to the right until they reach the central position, which is the beginning of the cycle of operation. When the piston 47 approaches the end of its left stroke inlet valve 80 is closed prior to the opening of exhaust valve 86, permitting of the expansion of the steam or the like to complete the power stroke. The rotatable timing element or cam disc 21 being connected with the pistons through the medium of connecting rods 55 and associated elements, serve to control the cycle of operation of the pistons, their timing, and to limit their extent of travel in opposite directions, preventing the pistons from impinging against the ends of their cylinders. Should the engine stop with the pivot of the connecting rods 55 on dead center, the rotatable timing element 21 may be turned to move the pivot off of dead center without turning the power distributing unit of the engine.

Upon the movement of the pistons 46 and 47, to the right, centralizing levers 61 and 61' are swung to the right shifting connecting rod 66 to the right. The jaws 36 and 37 of the gripping device now have gripping action with the flanges 27, turning the fly wheel 26. The arm 28 swings through a relatively short arc and the pivot 68 never gets upon dead center. When the pistons 46 and 47 reach the end of their right stroke, the right movement of the rod 66 is stopped, but operating arm 28 moves a short distance due to inertia and this relative movement between the arm 28 and rod 66 serves to swing the gripping device upon its pivot to bring jaws 36 and 37 out of engagement with the flanges 27. Hence when the pistons 46 and 47 travel to the left, gripping jaws 36 and 37 will travel over the flanges 27 without having clamping engagement therewith. When the centralizing lever 58 and 58' swing to the left, rod 69 is shifted to the left and the jaws 37 and 38 of the gripping device 41 now have gripping engagement with the flanges 27, turning the fly wheels 26. When the pistons reach the end of the left stroke,

the left movement of the rod 69 stops, and arm 29 moves slightly forwardly with relation to the rod 69, due to inertia, whereby the jaws 37 and 38 of the gripping device 41 are free from engagement with the flanges and will travel over the flanges without gripping engagement when the pistons again travel to the right.

It is to be understood that the form of my invention, herewith shown and described, is to be taken as a preferred example of the same, and that various changes in the shape, size and arrangement of parts, may be resorted to without departing from the spirit 15 of my invention, or the scope of the subjoined claims.

Having thus described my invention, I claim:—

1. In an engine, a pair of cylinders, inlet and outlet valves connected with one end of each cylinder, pistons within the cylinders, piston rod means connecting the pistons, centralizing levers arranged near the piston rod means and connected therewith to be shifted hereby, valve shifting means actuated by one centralizing lever, a rotary power distributing member, and means actuated by the centralizing levers to drive said member.

2. In an engine, a pair of cylinders, inlet and outlet valves connected with one end of each cylinder, pistons within the cylinders, piston rod means connecting the pistons, pairs of centralizing levers arranged near the piston rod means, centralizing links connected with the piston rod means and with the centralizing levers, valve shifting mechanism operated by one pair of centralizing levers, a rotatable power distributing member, and means operated by the two pairs of centralizing levers to drive the power distributing member.

3. In an engine, a pair of cylinders, inlet and outlet valves connected with one end of each cylinder, pistons within the cylinders, piston rod means connecting the pistons, pairs of centralizing levers arranged near the piston rod means, centralizing links pivotally connected with the piston rod means and with the centralizing levers, pairs of swinging levers connected with said valves, rods connecting the swinging levers in one pair with the swinging levers in the other pair, a pair of shoes carried by each rod, trip elements carried by the centralizing levers in one pair and disposed between the pairs of shoes for coaction therewith, a rotatable power distributing member, and intermittently operating devices connected with both pairs of centralizing levers to drive the member.

4. In an engine, a pair of cylinders, inlet and outlet valves connected with one end of each cylinder, pistons within the cylinders, piston rod means connecting the pistons, pairs of centralizing levers arranged near the piston rod means, centralizing links

pivotally connected with the piston rod means and with the pairs of centralizing levers, pairs of swinging levers connected with said valves, rods connecting the swinging levers in one pair with the swinging levers in the other pair, a pair of shoes carried by each rod, one shoe carried by one rod being disposed inwardly and in advance of the corresponding shoe carried by the other rod and one shoe carried by such other rod being disposed inwardly of and in advance of the corresponding shoe carried by the first named rod, trip elements carried by the centralizing levers in one pair and disposed between the pairs of shoes for co-action therewith, 70 a rotatable power distributing member, and intermittently operating devices connected with both pairs of centralizing levers to drive said member.

5. In an engine, a pair of cylinders, inlet and outlet valves connected with one end of each cylinder, a pair of cranks connected with the inlet and outlet valves of each cylinder, a pair of spaced stops arranged to limit the movement of each crank in opposite directions, a retractile coil spring connecting the cranks in each pair and adapted to shift them into engagement with corresponding stops of the pairs of stops when moved past dead center, pairs of swinging levers connected with the pairs of cranks, rods connecting the swinging levers in any one pair with the swinging levers in the other pair, a pair of shoes carried by each rod, pistons within the cylinders, piston rod means connecting the pistons, pairs of centralizing levers in one pair connected with the piston rod means, trip elements carried by the centralizing levers and arranged between the pairs of shoes to engage therewith, a rotatable power distributing member, and means operated by the both pairs of centralizing levers to drive the member.

6. In an engine, a pair of cylinders, pistons within the cylinders, piston rod means connecting the pistons, inlet and exhaust means for each cylinder, centralizing levers extending transversely of the piston rod means between the cylinders, means for pivotally supporting one centralizing lever upon one side of the piston rod means and the other centralizing lever upon the opposite side of the piston rod means, rods connected with the free ends of the centralizing levers, means connecting the centralizing levers with the piston rod means, a rotatable power distributing member, and intermittently operating devices connected with the rods to drive the member.

7. In an engine, a pair of cylinders, pistons within the cylinders, piston rod means connecting the piston, inlet and exhaust means for each cylinder, a rotatable stroke regulating element, a rod connected with the rotatable stroke regulating element and with

the piston rod means, a pair of centralizing levers extending transversely of the piston rod means, means for pivotally supporting the centralizing levers at points upon opposite sides of the piston rod means, a centralizing link pivotally connected with the piston rod means and with the centralizing levers, a rotatable member, rods pivotally connected with the free end portions of the centralizing levers, and gripping devices connected with the rods and adapted to engage portions of the rotatable member, said gripping devices operating in opposite directions.

8. In an engine, a pair of cylinders, pistons within the cylinders, piston rod means connecting the pistons, inlet and exhaust means for each cylinder, a rotatable stroke regulating element, a rod connected with the rotatable stroke regulating element and with the piston rod means, a pair of centralizing levers extending transversely of the connecting rod means and pivotally supported upon opposite sides of the same, a centralizing link pivotally connected with the piston rod means and with the centralizing levers, rods pivotally connected with the opposite free ends of the centralizing levers, a rotatable member embodying a band, a pair of operating levers disposed adjacent to the member and independently pivotally mounted concentrically with relation to the axis of rotation of the said member, gripping devices pivotally mounted upon the operating levers and arranged to engage with said band and connected with said rods, said gripping devices operating in opposite directions.

9. In an engine, a pair of cylinders, inlet and exhaust means arranged at one end of each cylinder, pistons within the cylinders, piston rod means connecting the pistons, centralizing levers pivotally supported upon opposite sides of the piston rod means and connected therewith to be driven thereby, a rotatable member, gripping devices engaging the rotatable member to turn the same, said gripping devices operating in opposite directions, rods connected with the gripping devices and with the free ends of the centralizing levers, a rotatable stroke regulating element, and a connecting rod connected with the timing element and with the connecting rod means, the stroke regulating element being rotatable in either direction independently of the direction of rotation of said member.

10. In an engine, a pair of cylinders, inlet and exhaust means connected with one end of each cylinder, pistons within the cylinders, piston rod means connecting the pistons, centralizing levers pivotally supported upon opposite sides of the piston rod means and connected with the same, a rotatable member, operating levers pivotally supported at the center of the rotatable member and extending in opposite directions, gripping devices

carried by the operating levers and engaging the rotatable member and operating in opposite directions, rods connected with the gripping devices and with the centralizing levers, a rotatable stroke regulating element, and a rod connecting the stroke regulating element with the connecting rod means, the stroke regulating element being rotatable in either direction independently of the rotation of said member.

11. In an engine, a pair of cylinders, inlet and exhaust means connected with one end of each cylinder, pistons within the cylinders, piston rod means connecting the pistons, centralizing levers pivotally supported upon opposite sides of the piston rod means and connected with the same, a rotatable member, operating levers pivotally supported at the center of the rotatable member and extending in opposite directions, gripping devices carried by the operating levers and engaging the rotatable member and operating in opposite directions, rods connected with the gripping devices and with the centralizing levers, a rotatable stroke regulating element, a rod connecting the stroke regulating element with the piston rod means, the stroke regulating element being rotatable in either direction independently of the rotation of said member, means including a centrifugal governor to control the supply of fluid pressure to the inlet means, and means whereby the centrifugal governor is driven by the stroke regulating element.

12. In an engine, a pair of cylinders, inlet and exhaust means connected with one end of each cylinder, pistons in the cylinders, piston rod means connecting the pistons, centralizing levers connected with the piston rod means, a rotatable member, gripping means to engage the rotatable member and connected with the centralizing levers, and a rotatable stroke regulating element connected with the piston rod means to regulate the stroke of the pistons.

In testimony whereof I affix my signature.
FRED A. GERLING.
